ATTORNEY.S.

UNITED STATES PATENT OFFICE.

GEORGE E. FRISZ AND JAMES D. WILTSHERE, OF INDIANAPOLIS, INDIANA.

WHEEL-PULLER.

1,328,663.

Specification of Letters Patent. Patented Jan. 20, 1920.

Application filed July 1, 1918. Serial No. 242,799.

To all whom it may concern:

Be it known that we, GEORGE E. FRISZ and JAMES D. WILTSHERE, citizens of the United States, residing at Indianapolis, in the county of Marion and State of Indiana, have invented certain new and useful Improvements in Wheel-Pullers, of which the following is a specification.

The present invention has relation to that type of tool or implement known generally as a wheel puller, but we desire it to be understood that this term is not used in its restrictive sense because the device is capable of utility for purposes other than comprehend by the expression, as will herein-after appear.

The primary object of our invention is to provide a device of this character by means of which to remove wheels, gears, spindles, etc., which will be as nearly universal as possible in respect to application to objects or elements of this nature of different shapes, sizes and construction. For example, the device in question is so constructed as to remove an automobile wheel equally as well as it will remove a gear or pinion from its shaft, and in respect to its wheel removing function the device is one that may be used for removing a wheel either by the spoke engaging method or by the hub engaging method, and when by the latter method is capable of application to substantially every style or size of hub thread now employed upon motor vehicles, regardless, furthermore, of whether the hubs are internally or externally threaded.

To this end the invention is provided with adjustable gripping or pulling instrumentalities interchangeable in character so as to accord with the work to be done.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a front elevation of a device constructed in accordance with my invention, showing the use of the threaded elements provided for engagement with wheel hubs;

Fig. 2 is a sectional view on the line 2—2 of Fig. 1;

Fig. 3 is a detail perspective of one of the threaded stud members; and

Fig. 4 is a fragmentary sectional view showing the use of the interchangeable pulling elements designed for pulling wheels by the spoke engagement method or for pulling gears, pinions and the like.

Fig. 5 is an enlarged fragmentary sectional view of the swiveled end of the pressure screw.

Fig. 6 is a perspective view of one of the stud members provided with convex threaded surfaces, as distinguished from the concave surfaces shown in Fig. 3.

Throughout the following detail description and on the several figures of the drawings, similar parts are referred to by like reference characters.

Referring to the drawing, 1 indicates a body member preferably recessed or chambered at one side as indicated at 2 and provided at its opposite side with radial webs 3 for strengthening the body. The body is provided with a threaded boss at its center to receive an adjustable pressure screw 4 which is designed to be engaged with the axle or shaft on which the wheel or gear to be removed is mounted. This screw as shown in Fig. 2 is preferably provided with a swiveled extremity 4' whereby to prevent injury to the object against which it is engaged.

The body 1 is provided with a series of radially extending slots 5 in which are mounted the desired object engaging elements by means of which the gear or wheel is positively gripped preparatory to the pulling operation. Where it is intended to pull an automobile wheel the type of element which is mounted in this slot takes the form, preferably, shown in Fig. 3. The member, it will be observed, is formed with a rectangular intermediate portion 6 where the said member engages with the walls of the slot in which it is mounted, this rectangular formation preventing the stud, as said member is termed for convenience, from rotating. At one end the stud is threaded to receive a clamping nut while at its opposite end it is poly-sided and the surface of each side suitably formed with threads as indicated at 8.

Preferably the threads on each face are either of a different size or of a different

type so that the stud will be of a construction to engage wheel hubs having different types or sizes of threads. It is to be understood that while the surfaces of the stud, which is shown in Fig. 3, are concave, we comprehend that studs provided with convex thread surfaces may also be utilized as shown in Fig. 6, so that the implement may be used for removing wheels by engagement with external or internal threads on the hub, as the case may be. Usually the hubs of truck wheels are internally threaded while the hubs of other types of motor vehicles are externally threaded, and hence the provision of the different types of studs referred to.

A very important feature of our device is the provision of a set screw or its equivalent, so arranged as to coact with the adjacent stud upon the outer side of the same and opposite to the face which is engageable with the wheel hub. In the drawing these studs are designated 9 and are radially arranged to be received by threaded openings in the periphery of the body 1 and screwed into engagement with the studs which are mounted in the radial slots 5 as hereinbefore described. The function of said set screws is to take up the strain which is placed upon the studs when the device is operated in the usual manner for pulling the object to be removed. In other words, the set screws 9 prevent the spreading of the stud members or the object engaging elements that may be mounted in the slots 5. In the use of the device these studs furthermore may be employed to obtain the proper adjustment of the object engaging elements into positive gripping or engaging position 40 with respect to the object which is to be pulled.

As shown in Fig. 4, we may substitute for the threading stud members shown in Fig. 3, pulling arms 10 each of which at one end is bent to provide a hook 11 and at the other end threaded to receive a clamping and adjusting nut 12. Obviously these arms may be adjusted radially with respect to the body 1 and axially with respect thereto, so that the arms may be made longer or shorter, according to the position of the part to be engaged thereby, or outwardly and inwardly according to the size of the object to be engaged. These arms are capable of being engaged with the peripheries of gears, and will take gears of different thicknesses because of the adjustment just above described. Or they may be engaged with the spokes of wheels if it is desired to remove the wheel by this method instead of by the hub engaging method.

Describing the use of the device, in removing wheels by engagement of the threaded stud members with the hub of the wheel, having first determined the proper thread

surface 8 of the stud which will correspond with the thread on the hub, the studs are adjusted in these slots so as to fit the particular hub. The body is then screwed upon the hub a sufficient distance and the screws 70 9 adjusted so as to hold the studs firmly against the hub. The pressure screw 4 is then screwed into contact with the spindle or axle of the wheel and enough pressure exerted thereupon to effect the displacement 75 of the wheel in the customary manner. A very considerable pressure may be exerted upon the pressure screw 4 because of the coaction of the set screws 9 with the threaded stud members which prevents any tendency of these last mentioned members to separate under the strain. With this coöperation, if it is desired to remove a wheel of a different size than the one previously removed, the threaded studs are moved outwardly or inwardly as found necessary in the slots 5 of the body.

When the device is used for removing gears, the arms 10 are substituted for the studs. Usually where arms of this character 90 are employed there is a tendency for said arms to spread, but this action is prevented as above mentioned, by the coaction of the set screws 9 therewith. If the gear to be removed is formed with threaded openings, 95 ordinary cap screws may be substituted instead of the arms or threaded studs herein described.

In addition to the use of the separate wheel-part engaging elements, in the manner above described, the two types of parts, by reasons of the interchangeability herein referred to may be used simultaneously. That is to say, where sufficient engagement is not likely to be afforded by either the 100 threaded studs alone or the pulling arms alone, both studs and arms may be used to engage the part to be removed, the threaded studs to engage the threaded portions of the hub, and the arms to engage the hub flange 110 or the spokes of the wheel as found convenient by virtue of the particular construction of the wheel or part to be removed. Furthermore, should the portions of the threaded hub which are engaged by the threaded 115 studs be mutilated by excessive pressure, the threaded studs where this occurs, may be removed and a pulling arm substituted, shifting the threaded studs to the relative position formerly occupied by the pulling 120 arm which is substituted.

Obviously, the device has a wide range of utility owing to the interchangeability of the parts employed, and the application of the device to the work to be done is greatly 125 facilitated because of the readiness with which the object engaging elements may be adjusted and held at adjusted positions. If desired, of course any one or more of the object engaging elements may be dispensed 130

with or adjusted to such position as not to 5
coact with the object to be removed, but
owing to the fact that a large number of
these object engaging elements, relatively
speaking, is employed, a better gripping ac-
tion is obtained than would be the case in
the event the number of such elements was
not so great.

Having thus described the invention, what
10 we claim as new is:

1. A universal puller device of the class
described comprising a body, a pressure pro-
ducing member mounted thereupon for ef-
fecting removal operation, and interchange-
able wheel part engaging members adapted
15 to be engaged with different parts of the hub
or member to be removed.

2. A device of the class described comprising
a body, a plurality of radially adjust-
able object engaging elements, means for
holding said elements at adjusted positions,
20 separate adjustable means coöperative with
each of said elements to prevent movement
thereof incident to stress thereupon during
operation, and a pressure member adjustably
25 mounted in said body.

3. A device of the class described comprising
a body having a series of slots formed
therein, object engaging elements mounted
30 in said slots, means for holding said ele-
ments at adjusted positions in the slots, an
adjustable setting member in said body ad-
jacent to each slot and its object engaging
35 element and arranged to contact with the
latter to prevent accidental movement of
said element, and a pressure screw disposed
for exerting pressure to produce movement
of the part engaged by said elements.

4. A wheel puller of the class described
40 comprising a body, a series of hub engaging
members adjustably mounted thereon, each
member being provided with differently
threaded surfaces whereby to enable appli-
cation to differently threaded hubs, and
45 means for imparting movement to said body.

5. A wheel puller of the class described
comprising a body, a series of poly-sided
hub engaging studs mounted thereon, each
50 stud side having its surface provided with
threads, and means for exerting pressure to
produce movement of the body.

6. A wheel puller of the class described
comprising a body, a series of poly-sided
hub engaging studs mounted thereon, each
55 stud side having its surface curved to con-
form to the shape of the hub with which it

is engageable and each face having a differ-
ent thread, and means for holding said studs
at adjusted positions.

7. A wheel puller of the class described 60
comprising a body, a series of poly-sided
hub engaging studs mounted thereon, each
stud side having its surface curved to con-
form to the shape of the hub with which it
is engageable and each face having a differ- 65
ent thread, means for holding said studs at
adjusted positions, means mounted on said
body for engagement with the face of said
stud opposite to its hub engaging face to
prevent accidental movement of the stud 70
when pressure is exerted thereupon, and
means carried by said body for imparting
movement thereto to effect removal opera-
tion.

8. A wheel puller of the class described 75
comprising a body, interchangeable object
engaging members adapted for disposition
in said body and adjustable axially and
radially of the body, and pressure means for
producing movement of the body when the 80
members are in engagement with the object
to be removed.

9. A wheel puller of the class described
comprising a disk-like body, object engaging
members mounted in said body and adjust- 85
able radially with respect to the axis of the
body and adjustable axially with respect to
said body, means for producing either of the
adjustments, and a threaded pressure mem-
ber mounted in said body for imparting 90
movement thereto when the object engaging
elements are in operative position with re-
spect to the object to be displaced.

10. A wheel puller of the class described 95
comprising a disk-like body having a series
of radiating slots formed therein, object en-
gaging members mounted in said slots and
adjustable radially with respect to the axis
of the body according to the size of the ob-
ject and adjustable axially with respect to 100
said body to produce a longer or shorter
reach of said members, a threaded pressure
member mounted in said body for imparting
movement thereto when the object engaging
elements are in operative position with re- 105
spect to the object to be displaced, and ad-
justable means for limiting the radial move-
ment of the object engaging members.

In testimony whereof we affix our signa-
tures.

GEORGE E. FRISZ.
JAMES D. WILTSHERE.
